UNITED STATES PATENT OFFICE.

CHARLES T. ANDERSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL INSTRUMENT.

1,284,966.

Specification of Letters Patent. Patented Nov. 19, 1918.

Application filed August 14, 1917. Serial No. 186,162.

To all whom it may concern:

Be it known that I, CHARLES T. ANDERSON, a citizen of the United States, residing at Edgewood borough, in the county of Allegheny and State of Pennsylvania, have invented certain new and useful Improvements in Electrical Instruments, of which the following is a specification.

My invention relates to electrical instruments, and particularly to instruments having a group of two or more contact fingers mounted on one common supporting member.

One object of my invention is the provision of means for keeping the fingers of such a group in alinement. The invention is particularly well adapted to electrical relays, and I will describe it as applied to such, although it is understood that the invention is not limited to such application.

I will describe one form of device embodying my invention and will then point out the novel features thereof in the claim.

In the accompanying drawings, Figure 1 is a view showing in front elevation a portion of a relay including one form of device embodying my invention. Fig. 2 is a view showing in end elevation the portion of the relay and the device shown in Fig. 1.

Similar reference characters refer to similar parts in each of the views.

Referring to the drawing, R designates a portion of a relay which, as here shown, comprises two windings W and W', two pole-pieces P one for each winding, and an armature A pivotally mounted in non-magnetizable brackets X attached to the pole-pieces. The armature A carries a group of contact fingers F, which fingers are adapted to engage stationary contact blocks B when armature A is in the attracted position. As best shown in Fig. 2, each contact finger F comprises a relatively rigid arm 10 secured to but insulated from the armature by means of insulating studs K. One end of the bar 10 is bent in the form of a V, and secured to the free end of this bent portion is a contact spring 11, the outer end of which coacts with the corresponding fixed block B. It is understood that the arm 10 and the spring 11 are of electro-conductive material.

One important requirement of a relay, especially of a relay used in railway signaling, is that the electrical resistance of each contact, that is, the resistance between the finger F and the block B, shall be a minimum value. This means that the pressure between the two must be a predetermined value and that the finger must be properly alined so that it exerts a uniform pressure against the block throughout the length of the contacting edge of the finger. This adjustment is secured, when the relay is manufactured, by bending arm 10 or spring 11, or both, but such adjustment may not be permanent because, after long continued use, the parts of the contact finger may become distorted or bent.

To avoid such distortion of the fingers, I provide means for rigidly connecting all of the fingers F so that each finger is permanently held in the position of its original adjustment. As here shown, this means is in the form of a clamp H comprising two co-extensive rigid strips 13 of insulating material, which strips are provided at spaced intervals with registering openings to receive bolts 14 for clamping the strips together. As shown, the clamp H is of sufficient length to embrace the springs 11 of all of the contact fingers F, the strips being arranged upon opposite sides of the springs while the bolts extend through the strips at points between the fingers, as best shown in Fig. 1.

In constructing the relay, all of the parts shown in the drawing, except the clamp H, are first assembled, and each finger F is then adjusted so that it is properly alined with respect to its block B and so that it bears against this block with the desired pressure when the armature is in the fully attracted position. The strips 13 of the clamp H are then arranged on opposite sides of the springs 11, and the bolts 14 are tightened, thus securely clamping the springs between the strips. The clamp is preferably located as nearly as practicable to the contacting edges of the springs.

It will be clear from the foregoing that after the contact fingers are thus adjusted and clamped, no one finger in the group can become distorted, nor can any one finger be-

come bent out of alignment with respect to the remaining fingers in the group. In other words, by means of the clamp H the original contact pressure and alignment of the fingers, and so the original contact resistance, are preserved throughout the life of the relay.

Although I have shown and described only one form of device embodying my invention, it is understood that various changes and modifications may be made therein within the scope of the appended claim without departing from the spirit and scope of my invention.

Having thus described my invention, what I claim is:

An electrical instrument comprising a movable contact operating member, a group of contact fingers each attached adjacent one end to said operating member, and means for clamping said fingers together adjacent their other ends.

In testimony whereof I affix my signature in presence of two witnesses.

CHARLES T. ANDERSON.
